US00D444987S

(12) **United States Design Patent** (10) Patent No.: **US D444,987 S**
 McGrath et al. (45) Date of Patent: ** Jul. 17, 2001

(54) **FILTERED WATER CARAFE**

(75) Inventors: **Kevin Peter McGrath**, Alpharetta;
Malcolm Daniel Poirier, Marietta;
Bruce Scott Williamson, Alpharetta;
Jeffrey Eldon Fish, Dacula, all of GA
 (US); **Paul Metaxatos**, Collinsville;
Dave Mathieu, Middleton, both of CT
 (US)

(73) Assignee: **Kimberly-Clark Worldwide, Inc.**,
 Neenah, WI (US)

(**) Term: **14 Years**

(21) Appl. No.: **29/107,207**

(22) Filed: **Jun. 29, 1999**

(51) LOC (7) Cl. **07-01**

(52) U.S. Cl. **D7/319**; D7/317

(57) **CLAIM**

We claim the ornamental design for a filtered water carafe,
 as shown and described.

DESCRIPTION

FIG. 1 is a side view of the filtered water carafe.

FIG. 2 is a front view of the filtered water carafe.

FIG. 3 is a rear view of the filtered water carafe.

FIG. 4 is a bottom view of the filtered water carafe; and,

FIG. 5 is a top view of the filtered water carafe.
